[57] CLAIM

The ornamental design for a pacifier holder, as shown and described.

DESCRIPTION

FIG. 1 is a top perspective view of a pacifier holder, showing my new design in use position; the broken line showing is for illustrative purposes only and forms no part of the claimed design;

FIG. 2 is a bottom plan view thereof in non-use position;

FIG. 3 is a right side elevational view thereof;

FIG. 4 is a top plan view thereof;

FIG. 5 is a left side elevational view thereof;

FIG. 6 is a bottom plan view of a second embodiment of the pacifier holder in use position;

FIG. 7 is a right side elevational view thereof, the left side elevational view being identical; and all other views being identical to that shown in FIGS. 1-5; and

FIG. 8 is a bottom plan view of FIG. 1 in use position. The cross-line pattern which is partially shown for ease of illustration in FIGS. 1-8, represents a conventional fabric.
